UNITED STATES PATENT OFFICE.

EDWARD G. CARR, OF OAKLAND, CALIFORNIA.

TEMPLET FOR CONCRETE-TAMPERS.

1,282,043.

Specification of Letters Patent. Patented Oct. 22, 1918.

Application filed October 4, 1916. Serial No. 123,765.

To all whom it may concern:

Be it known that I, EDWARD G. CARR, a citizen of the United States, and a resident of Oakland, in the county of Alameda and State of California, have invented certain new and useful Improvements in Templets for Concrete-Tampers, of which the following is a specification.

My invention relates to concrete tampers and more particularly to the templets used in such tampers of the type disclosed in my Patents No. 1203482, dated Oct. 31, 1916, and No. 1204245, dated November 7, 1916.

In making concrete roads having a turn or bend in the same the general practice is to make the surface of the curved portion flat and inclined toward the inside of the road or "banking" as it is called and the straight portions of the road have a crown, the roadway dipping gradually to each side thereof to the gutter or edge; this of course necessitates the lower face of the templet being curved to conform to and create the crown; it will of course be seen that such curved base templets cannot be used on the curved portions of the road which as hereinbefore pointed out is made flat.

One object, therefore, of this invention is to provide a templet applicable for use on flat or crowned beds.

A further object is to provide a templet with means for adjusting the active working edge to varying curvatures.

With these and other objects in view this invention consists in certain novel features of construction, arrangement of parts as will be hereinafter more fully described and then pointed out in the claims, reference being had to the accompanying drawings in which—

Figure 1 is a front elevation of an embodiment of my invention.

Fig. 2 is a vertical transverse section on line 2—2 of Fig. 1.

Fig. 3 is an end elevation.

Fig. 4 is an enlarged perspective view of one of the clamp brackets.

In the drawing which exhibits one embodiment of my device the master templet is represented by the character 10 and comprises a beam of wood or other suitable springy or flexible material having its lower face or edge curved as indicated by the lower dotted line 11 in Fig. 1, this curvature being such as to accommodate the face to

the usual convexity of road beds as usually constituted; the templet is widest vertically at its central portion the upper face of said central portion being a horizontal plane, the templet tapering toward each end. 60

In Fig. 4 is shown a clamp which has a front wall 12 and a rear wall 13, both walls having an elongated slot as indicated by 12^a and 13^a; the front wall has an angled extension 12^b which forms a bracket to which is bolted the auxiliary templet 14 which is practically the same length as the master templet 10 but has straight upper and lower faces; this auxiliary templet is much lighter than the master templet and is composed of some springy material and is bolted to said master templet, adjacent its ends so that while it may have a slight movement at its ends it is free to be flexed between the same. 70

The clamps 12, which in the present form of device, are two in number, are slipped over the central portion of the master templet and held thereon by bolts 15 passed through said templet and through the slots in the front and rear walls of the clamp; 80 and nuts 16 screwed on the threaded ends of the bolts. Through the upper end of each clamp a screw shaft 17 having a handle 18, is threaded the lower end 19 of the screw bearing against the upper face of the master templet. 85

This tamping device is designed to be used with either of my concrete tampers hereinbefore referred to, or it may be used with any tamper or device for rodding off concrete road beds. 90

In order to use the device on curves, bends or flat roads the parts are in the position indicated in Fig. 1, and the tamping will be done by the flat lower face of the auxiliary templet 14. 95

When however, the device is to be used on the straight portion of a road or on the usual crowned roads, the longitudinal contour of the lower face of the auxiliary templet 100 must be changed to conform to the contour of the crowned road bed; to do this the nut 16 is loosened which leaves the clamp freely to move relatively to the body of the templet; now by screwing the lower end of screw 105 shafts 17 down against the upper face of the master templet the clamps will rise carrying the auxiliary templet upward with them, and as the ends of the auxiliary templet have very slight movement the templet be- 110

tween the points of end attachment will become flexed and the contour of the lower face of the same will become curved the degree of which will be governed by movement 5 of the clamps; when the desired curvature is secured the nuts 16 are screwed tightly against the clamps securely holding the auxiliary templet in place and with its lower face flexed to the necessary curvature.

10 Any number of clamps and correlated bending devices may be used as occasion may require.

While I have illustrated in the drawings 15 a very desirable simple and novel tamping device and means for changing the curvature of the active face of the same, I do not wish to limit my protection to the specific construction and operation illustrated, as the claims themselves will define the scope 20 of the invention.

I claim:—

1. A concrete tamper comprising a master templet, an auxiliary templet adjacent its lower end and held alongside the same, 25 and means for flexing the lower face of the auxiliary templet.

2. A concrete tamper comprising a master templet, an auxiliary templet adjacent its lower end and held alongside the same, 30 and means carried by the master templet for flexing the lower face of the auxiliary templet.

3. A concrete tamper comprising a master templet, an auxiliary templet coextensive longitudinally therewith adjacent its lower end and held alongside the same and means for changing the contour of the lower face of the auxiliary templet.

4. A concrete tamper comprising in combination a master templet having a normally curved lower face, an auxiliary templet having a flat lower face and held alongside the master templet and adjacent its lower end, and means for flexing the lower face of the auxiliary templet to conform to the curvature 45 of the lower face of the master templet.

5. A concrete tamper consisting of a master templet having a normally curved lower face, an auxiliary templet held at its ends 50 adjacent the lower end of the master templet and alongside of the same, the lower face of said auxiliary templet having a continuous normally flat lower face, and means carried by one templet and engaging the

other templet to flex the lower face of the 55 auxiliary templet.

6. A concrete tamper comprising in combination a master templet, a clamp slidably held on the same, an auxiliary templet secured at its ends to the master templet 60 alongside the same and adjacent its lower end, the lower face of the auxiliary templet being normally flat from end to end, said templet rigidly secured to said clamp, and means carried by the clamp to flex the lower 65 face of the auxiliary templet.

7. A concrete tamper comprising in combination a master templet, an auxiliary templet secured at its ends to the master templet alongside the same and adjacent its 70 lower end, a clamp member mounted on said master templet and comprising front and rear walls slidably engaging the templet, the front wall rigidly secured to the auxiliary templet, and screw means carried by 75 the clamp to flex the lower face of the auxiliary templet.

8. A concrete tamper comprising in combination a master templet and an auxiliary templet secured at its ends to the master 80 templet alongside the same and adjacent the lower end thereof, a clamp member fitted to the master templet having slotted front and rear walls slidably engaging the master templet, the front wall offset and rigidly secured at its lower end to the auxiliary templet, a bolt passing through said master templet and the slots of the clamp, a clamp nut carried by said bolt to lock the clamp member to the master templet and a screw shaft 90 slidable through the upper wall of the clamp and adapted to engage the upper face of the master templet, whereby the lower face of the auxiliary templet may be flexed to cause 95 curvature of the same.

9. A templet for concrete tampers consisting of a main or body portion and an auxiliary templet held adjacent its lower end and alongside the same and secured thereto at the ends thereof.

10. A templet for concrete tampers comprising a rigid master templet and a flexible auxiliary templet positioned adjacent its lower end.
